(57) **CLAIM**

The ornamental design for a computer processor enclosure, as shown and described.

DESCRIPTION

FIG. 1 is a front isometric view of a computer processor enclosure, showing our new design;

FIG. 2 is a front view thereof;

FIG. 3 is a left view thereof;

FIG. 4 is a top plan view thereof;

FIG. 5 is a back view thereof; and,

FIG. 6 is a rear isometric view thereof.

The right view is similar to the left view illustrated in FIG. 3.
